UNITED STATES PATENT OFFICE.

WILLIAM G. WILLIAMS, OF VINITA, OKLAHOMA.

ATTACHMENT FOR SUITCASES AND THE LIKE.

1,062,752.

Specification of Letters Patent.

Patented May 27, 1913.

Application filed December 7, 1911. Serial No. 664,483.

To all whom it may concern:

Be it known that I, WILLIAM G. WILLIAMS, a citizen of the United States, residing at Vinita, in the county of Craig 5 and State of Oklahoma, have invented a new and useful Attachment for Suitcases and the Like, of which the following is a specification.

This invention relates to protecting and 10 reinforcing attachments for suit cases and the like, one of its objects being to provide a metallic case or frame adapted to be folded upon a suit case so as to protect the edge and corner portions and to entirely cover 15 the top thereof and to afford means for properly supporting the case when used for carrying heavy loads which would tend to bend or otherwise distort an ordinary suit case when used without some reinforcing 20 means.

Another object is to provide a device of 25 this character which can be readily applied, will not detract from the appearance of the suit case when used in connection therewith, and which can be provided with any suitable means for fastening the structure upon a suit case and for facilitating the transportation of the device.

With the foregoing and other objects in 30 view which will appear as the description proceeds, the invention resides in the combination and arrangement of parts and in the details of construction hereinafter described and claimed, it being understood 35 that changes in the precise embodiment of the invention herein disclosed can be made within the scope of what is claimed, without departing from the spirit of the invention.

In the accompanying drawings the pre- 40 ferred form of the invention has been shown.

In said drawings:—Figure 1 is a perspective view of the attachment in position upon a suit case. Fig. 2 is a section on line A—B. Fig. 1. Fig. 3 is a perspective view of the 45 attachment with the handle, locks and other parts removed therefrom.

Referring to the figures by characters of reference 1 and 2 designate top plates each having end flanges 3 and a side flange 4 de- 50 pending therefrom. Depending side strips 5 angular in cross sectional contour, project from the flanges 3 and 4 where they merge into each other and these side strips are formed integral with bottom strips 6 which 55 are likewise angular in cross sectional contour and are parallel with the plates 1 and

2. Each of the bottom strips has tongues 7 extending inwardly therefrom, each tongue alining with the corresponding tongue on the opposed strip 6 and the alining tongues 60 being connected by hinges 8. A handle 9 is preferably connected to one of the plates (2) and a lock 10 of any desired form may be mounted on the plates for securing them in contact, as shown in Fig. 1. Furthermore 65 supplemental fastening devices such as shown at 11, may be mounted on the plates 1 and 2.

In using the device the plates 1 and 2 are unlocked from each other and the two halves 70 of the attachment are swung apart on the hinges 8. The suit case or other receptacle to be reinforced is then placed between the two sections of the attachment so as to rest on the tongues 7. When the said sections 75 are swung together, the angular strips 5 and 6 will straddle the edge portions of the suit case and protect them as well as the corners of the receptacle. The plates 1 and 2 will rest close to the top of the receptacle. 80 After the attachment has been thus placed in position the plates 1 and 2 can be fastened together and the entire structure can then be conveniently carried by means of the handle 9. The attachment can be made 85 as a separate article in which a suitcase can be easily placed or from which it can be quickly moved. If preferred, however, the said attachment can be riveted or otherwise secured to opposed separate sections similar 90 to the sections of a suit case or the like so as to constitute a permanent part of the receptacle thus formed. Thus it will be seen that the hinges connecting the two sections of the attachment become the hinge connec- 95 tions between the two separate sections so that, by unfastening the top plates 1 and 2 from each other, the receptacle can be opened upon its hinges 8.

Reinforcing devices such as constituting 100 the present invention are to be placed on the market as complete articles and will be made in different sizes so as to receive receptacles C of different sizes and proportions. The entire attachment can be made of any pre- 105 ferred material, such as brass, nickel, aluminum or the like and by using it, suit cases or similar receptacles which would otherwise be unfit for use, can be employed for carrying heavy articles or in fact for 110 any purposes to which a suit case is ordinarily put.

What is claimed is:—

A suit case receiving and reinforcing structure including opposed rigid frame sections, each formed in a single piece and consisting of a top plate flanged at its ends and along one side, an angular bottom strip, angular side strips connecting the ends of the top and bottom strips, and tongues extending inwardly from the bottom strip, hinge connections between the tongues of the op-

posed sections, means upon the top plates for securing them together, and a handle upon one of the plates.

In testimony that I claim the foregoing as my own, I have hereto affixed my signature in the presence of two witnesses.

WILLIAM G. WILLIAMS.
